AIR CONTROL MEANS FOR COMBUSTION APPARATUS

Clark Scholl, Springfield, Ohio, assignor to The Steel Products Engineering Company, Springfield, Ohio, a corporation of Ohio

Application October 19, 1935, Serial No. 45,776

13 Claims. (CL 230—114)

The present invention relates to improvements in automatic air control means for combustion apparatus, and has particular reference to a new and improved automatic damper for controlling the supply of air under pressure to the fuel bed of a furnace, as for example in the retort of an underfeed coal stoker.

It is well recognized that a proper ratio of fuel and finely dispersed air must be maintained in order to obtain efficient and satisfactory combustion. Such ratio is difficult to obtain in stokers with forced draft because of variations in operating conditions influencing the amount of air supplied to the combustion zone. In one common type of underfeed stoker, fuel is fed through a duct into the bottom of a retort to form a fuel bed, and air for combustion is supplied under pressure by a fan or blower through a duct to a plenum chamber, and then through tuyère openings into the bed. When the fuel bed is heavy and dense, the static pressure of the air will be relatively high, and at times may reach the maximum that the blower can develop. Conversely, when the fuel bed is thin and porous, its resistance to the passage of air is greatly reduced, and hence the static pressure of the air may be very low. The volume of air delivered by the blower varies inversely with the static pressure in the air passages. Thus, when the fuel bed is heavy, and the volume of air should be correspondingly high, the actual volume of air supplied is relatively low. When the fuel bed is light, and a relatively small amount of air is required, the amount of air actually supplied may be considerably in excess of that required for combustion, thus resulting in serious heat losses. The condition of the fuel bed is determined by the kind of fuel that is used, the rate of fuel feed, and the rate of combustion.

One of the primary objects of the present invention resides in the provision of novel means for supplying air under pressure automatically in accordance with the conditions of the fuel bed, thereby avoiding the inconvenience of and necessity for manual supervision and adjustment, and the undesirable consequences of failure to make proper adjustments.

Another object is to provide an automatic damper for the air supply means which is responsive to the static pressure of the air passing to the fuel bed so that when the static pressure increases, the damper is moved correspondingly toward open position, and when the static pressure drops, the damper is moved correspondingly toward closed position to restrict the flow of air,

thereby permitting the fuel bed to build up to the proper depth, and preventing substantial combustion losses because of an undue volume of excess air.

A more specific object resides in the provision in an air blower of a novel rotary inlet damper automatically adjustable in accordance with the varying height of a liquid which is responsive in level to the differential between the static pressure of the air delivered by the blower and the pressure of the atmosphere.

A general object resides in the provision of a new and improved damper of the foregoing character which is simple and inexpensive in construction, and sensitive, accurate and reliable in operation.

Further objects and advantages will become apparent as the description proceeds.

In the accompanying drawings, Figure 1 is a plan view of an underfeed stoker provided with automatic air supply means embodying the features of my invention.

Fig. 2 is a fragmentary vertical sectional view on an enlarged scale taken along line 2—2 of Fig. 1, and illustrating the automatic air supply means.

Fig. 3 is an axial sectional view of the blower taken along line 3—3 of Fig. 2.

Fig. 4 is a horizontal sectional view taken along line 4—4 of Fig. 2.

Fig. 5 is a vertical sectional view of a modified form of the invention.

Referring more particularly to the drawings, the underfeed stoker disclosed in Fig. 1 has a burner 10 comprising an upwardly opening fire pot or retort 11, a plenum chamber 12 surrounding the pot, and tuyères 13 opening from the chamber to the top of the pot. Solid fuel, such for example as coal, is fed by a conveyer 14 from a hopper 15 through a duct 16 into the bottom of the fire pot 11 to form a fuel bed. Air under pressure is supplied by a fan or blower 17 through a duct 18 to the plenum chamber 12 for discharge through the tuyères 13 into the top portion of the fuel bed. The conveyer 14 and blower 17 are driven in timed relation through a variable speed mechanism 19 from an electric motor 20. Preferably, the blower 17, the variable speed mechanism 19, and the motor 20 are rigidly mounted on the base of the hopper 15.

The blower 17, which constitutes the air supply means, may be of any suitable character, and is herein shown as of the rotary type. More particularly, the blower 17 comprises a generally cylindrical housing 21 which has a tangential

outlet 22 connected to the duct 18, and which is formed in one side wall with a circular opening 23. A rotor or fan wheel 24 is fixed on a shaft 25 for rotation within the housing 21, and comprises a plurality of annularly arranged peripheral vanes 26 defining a hollow interior space 27 open at one side and closed at the other side. The shaft 25 is driven by the motor 20. Attached in fixed position to the housing 21 about the front opening 23 is a ring 28 having an inwardly tapering conical flange 29 for directing air to the interior space of the rotor 24.

An important feature of the present invention resides in the provision of novel air control means, preferably in the form of a damper, which serves to control the volume of air supplied through the duct 18 to the fuel bed, and which is automatically adjustable in accordance with changes in the static pressure of the air. The damper may be of any desired form or type, and may be located in any suitable position of control in the air supply system. In the preferred form of the invention, the air supply is controlled at the inlet of the blower 17 by a damper 30 of the rotary type. Preferably, the damper 30 comprises a fixed plate 31 integral with the ring 28, which constitutes a rim therefor, and a flat circular rotary plate 32 disposed against the outer face of the plate 31. The fixed plate 31 is formed with an inwardly extending axial hub 33 supporting a fixed shaft 34 on the outer end of which the plate 32 is suitably journaled. Also secured to the shaft 34 within the wheel 24 is a generally conical deflector 35 for directing the incoming air toward the vanes 26. The fixed and movable plates 31 and 32 are formed respectively with radial uniformly peripherally spaced openings 36 and 37 adapted to be moved progressively into different degrees of communication between zero and full registration.

The damper plate 32 is rotatably adjustable to adjust the effective air inlet and hence the air intake of the blower 17 in accordance with variations in the static pressure of the air supplied to the fuel bed. In the preferred embodiment of the invention, this is accomplished through the medium of a liquid 38 which tends to seek different levels in accordance with changes in the differential between the static pressure of the air delivered by the blower 17 and atmospheric pressure, and which actuates an adjusting member 39 operatively connected to the damper plate 32. The liquid 38 is placed in a reservoir 40 which is divided by a partition 41 at the top into two chambers 42 and 43 intercommunicating under the liquid level. One chamber 42 is sealed from the atmosphere, and is connected above the liquid level through a passage 44 with the interior of the duct 18. The other chamber 43, although substantially closed by a cover 45, is open at the top to the atmosphere. When the stoker is idle, and atmospheric pressure prevails in the duct 18, the liquid 38 will assume the same level in both chambers 42 and 43 as indicated at 46. However, when the stoker is operating, the static pressure in the duct 18 will exceed atmospheric pressure more or less, and will depress the liquid in the chamber 42 accordingly, for example to the level 47, and thereby will cause a corresponding rise of the liquid in the chamber 43 to the level 48. The adjusting member 39 is movable in response to the variations in liquid level.

In Fig. 2, the reservoir 40 is elongated and rectangular, and extends along and is directly secured to one side of the duct 18. The passage 44

is defined by registering openings in the contacting walls of the duct 18 and the reservoir 40. The chambers 42 and 43 preferably are disposed in opposite ends of the reservoir 40, and hence are located side by side with an interconnecting passage 49 beneath the partition wall 41. The adjusting member 39 is shown in the form of a float in the chamber 43, which is of greater height and of less horizontal area than the chamber 42, and has a vertical connecting rod or stem 50 extending upwardly loosely through an opening 51 in the cover 45. Pivotally connected at one end to the upper end of the rod 50 is a lever 52. The other end of the lever 52 is connected through a swinging link 53 to the damper plate 32. Intermediate its ends, the lever 52 is mounted for pivotal movement on a horizontal axis between two centers 54 adjustably secured in two upstanding arms 55 of a bifurcated bracket 56 rigidly mounted on one end of the reservoir 40.

It will be seen that if the fuel bed is light and porous, the static pressure in the duct 18 will be low. As a result, the float 39 will be lowered to restrict the flow of air through the damper 30. Hence, the supply of air to the fuel bed, although adequate, will be cut down, thereby giving the fuel bed a chance to build up to the proper depth, and preventing an undue volume of excess air from passing through the fuel bed and diluting the products of combustion. As the fuel bed increases in depth and the holes fill up, the static pressure increases, thereby increasing the damper opening. Thus, the correct damper adjustment is automatically maintained at all times. The adjustment is substantially in accordance with the condition of the fuel bed, and takes into account the kind of fuel burned, the rate of feed and the rate of combustion in so far as these factors effect the condition of the fuel bed. The aggregate area of the openings 36 and 37, also of the openings 38, preferably is at least as great, if not greater, than the area circumscribed by the flange 29 so that there will be no restriction in the flow of the air by the damper 30 when the latter is wide open.

In the modification shown in Fig. 5, the automatic damper controls the flow of air from the blower 17 rather than the air entering the blower. The damper comprises a plate 32^a mounted within the duct 18 for pivotal movement about a horizontal axis 34^a into different angular positions relative to the path of air flow. The operating mechanism for the pivotal damper plate 32^a, except for minor differences hereinafter described, is closely similar to that for the rotary damper plate 32, and hence like parts thereof are designated by the same reference numerals plus the subscript ^a.

In this form, the reservoir 40^a is mounted on the top of the duct 18, and the passage 44^a opens from the duct upwardly through one end of the chamber 42^a to the top of the liquid 38^a. The cover 45^a for the chamber 43^a has a central cylindrical upstanding dome 57 formed with a series of peripherally spaced openings 51^a to the atmosphere. The damper plate 32^a is operable by a rod 58 to which it is pivotally connected at one side of the axis 34^a, and which extends upwardly from the duct 18 through a vertical tube 59 encircled by the annular float 39^a. The lower end of the tube 59 is threaded into a flanged opening 60 in the bottom of the chamber 43^a and in registration with an opening 61 in the top wall of the duct 18, and the upper end extends to above the maximum possible liquid level. An inverted cup 75

62, fixed centrally on the top of the float 39^a, and sealed internally from the chamber 43^a, is pivotally connected to the upper end of the rod 58, and is adapted to telescope loosely onto the 5 tube 59 or into the dome 51.

I claim as my invention:

1. An automatic damper for forced-draft stokers comprising, in combination with a rotary blower having a discharge duct and an axial 10 atmospheric air inlet, a fixed damper plate extending across said inlet, a rotary damper plate mounted in cooperative relation against said fixed damper plate, said plates having air inlet openings movable respectively into different degrees 15 of registration to define the effective air inlet area, and means located outside of said duct for automatically adjusting said rotary plate to increase and decrease said air inlet area respectively in accordance with increases and decreases in 20 the static pressure of the air discharged from said blower.

2. An automatic damper for forced-draft stokers comprising, in combination with a rotary blower having a discharge duct and having an 25 air inlet, a fixed damper member extending across said inlet, a rotary damper member mounted in cooperative relation against said fixed damper member, said members being flat and having air inlet openings movable respectively 30 into different degrees of registration to define the effective air inlet area, a stationary reservoir adapted to contain a liquid varying in level in accordance with changes in the static pressure of the air flowing through said duct, and means 35 operable in response to variations in the level of said liquid for automatically adjusting said rotary member.

3. An automatic damper for forced draft stokers comprising, in combination with a rotary 40 blower having a peripheral discharge duct and having an air inlet in one side, a fixed damper member for said inlet, a rotary damper member mounted in cooperative relation with said fixed damper member, said members having air inlet 45 openings movable respectively into different degrees of registration to define the effective air inlet area, a stationary reservoir having two liquid chambers in intercommunication below the liquid level, one of said chambers being closed 50 to the atmosphere and being in communication above the liquid level with said duct, the other of said chambers being open to the atmosphere, and means operable in response to variations in liquid level in one of said chambers for adjusting 55 said damper automatically in accordance with variations in the static pressure of the air in said duct.

4. An automatic damper for forced draft stokers comprising, in combination with a rotary 60 blower having a hollow propeller and having a casing with a peripheral discharge duct and an air inlet opening in one side, a fixed damper plate secured to said casing across said inlet and having a conical flange for directing air into 65 said propeller, a rotary damper plate mounted in cooperative relation against said fixed damper plate, said plates having air inlet openings movable respectively into different degrees of registration to define the effective air inlet area, the aggregate area of the openings in each 70 damper plate being no less than the area circumscribed by said flange, and means out of the path of air flow through said duct and adjustable in response to variations solely in the static 75 pressure of the air in said duct for adjusting said

rotary plate to effect a proportionate adjustment of said inlet area.

5. An automatic damper for forced draft stokers comprising, in combination with a rotary blower having a discharge duct and having an axial 5 atmospheric air inlet, a fixed damper plate extending across said inlet, a rotary damper plate mounted in cooperative relation against said fixed damper plate, said plates having air inlet openings movable respectively into different degrees 10 of registration to define the effective air inlet area, means defining two chambers containing a liquid in intercommunication below the liquid level, one chamber being closed to the atmosphere and being connected above the liquid 15 level to said duct, the other chamber being open above the liquid level to the atmosphere, a float on the liquid in said other chamber, and means operatively connecting said float to said rotary plate to control said air inlet area in accordance 20 with changes in the static pressure in said duct to increase the air flow upon an increase in static pressure and to reduce the air flow upon a decrease in static pressure.

6. An automatic damper for forced draft stokers comprising, in combination with a blower having a discharge duct and having an air inlet, a fixed damper member for said inlet, a rotary damper member mounted in cooperative relation with said fixed damper member, said members 30 having air inlet openings movable respectively into different degrees of registration to define the effective air inlet area, means defining two chambers containing a liquid in intercommunication below the liquid level, one chamber being 35 relatively large and shallow, being closed to the atmosphere and being connected above the liquid level to said duct, the other chamber being relatively small and deep and being under a substantially constant pressure above the liquid 40 level, a float on the liquid in said other chamber and spaced from the walls thereof, and movement multiplying means operatively connecting said float to said rotary member to control said air inlet area in accordance with changes in the 45 static pressure in said duct.

7. An automatic damper for forced-draft stokers comprising, in combination with a forced draft supply means having a discharge air-flow duct and an air inlet, a rotary damper for adjusting the effective area of the air inlet, a liquid reservoir having a partition defining two liquid chambers intercommunicating below the liquid level, one of said chambers being closed to the atmosphere and in communication above the liquid 55 level with said duct, the other of said chambers being open above the liquid level to the atmosphere, a float in said other chamber, a lever pivotally mounted intermediate its ends on said reservoir and having a link connection at one 60 end with said float and a link connection at the other end with said damper, whereby vertical movement of said float will effect a proportionate angular adjustment of said damper.

8. An automatic damper for forced draft stokers comprising, in combination with a blower having a discharge duct and an air inlet, a damper for adjusting the effective area of the air inlet, a liquid reservoir having a partition defining two rectangular liquid chambers juxtaposed end to end and intercommunicating below the liquid level, one of said chambers being relatively large and closed to the atmosphere and in communication above the liquid level with said duct at the discharge side of said damper, a float 70 75

in the other chamber which is relatively small and open above the liquid level to the atmosphere, and movement multiplying means operatively connecting said damper and said float for synchronous movement, whereby vertical movement of said float in response to varying liquid levels will effect a proportionate adjustment of said damper.

9. An automatic damper comprising, in combination with an air-flow passage, an adjustable damper for controlling the volume of air flowing through said passage, a liquid reservoir having two liquid chambers intercommunicating below the liquid level, one of said chambers being closed to the atmosphere and in communication above the liquid level with said passage at the outlet side of said damper, the other of said chambers being open above the liquid level to the atmosphere, a float in one of said chambers, a lever having a fixed fulcrum and having pivotal connections with said float and said damper whereby movement of said float in response to varying liquid levels will effect a proportionate adjustment of said damper.

25 10. An automatic damper comprising, in combination with an air flow passage, an adjustable damper for controlling the volume of air flowing through said passage, a reservoir having two liquid chambers of unequal height and of unequal 30 horizontal areas in intercommunication below the liquid level, the chamber of larger area being closed to the atmosphere and in communication above the liquid level with said passage at the outlet side of said damper, and a float in the 35 chamber of smaller area operable in response to variations in liquid level for adjusting said damper automatically in accordance with variations in the static pressure of the air in said passage.

11. An automatic damper for forced-draft 40 stokers comprising, in combination with a rotary blower having an air inlet and a discharge duct, a low pressure air damper in control of all of the air passing to said duct and adjustable to vary the effective area of said air inlet from zero to 45 maximum, and means including a float movable in response to variations in the pressure of the air in said duct and connected by a movement

multiplying means to said damper to effect a proportionate variation in the air inlet area.

12. An automatic damper comprising, in combination with an air duct and means for supplying air under pressure to said duct, a damper 5 pivotally mounted in said duct, a liquid reservoir mounted on said duct and having a partition defining two liquid chambers in intercommunication below the liquid level, one of said chambers being closed to the atmosphere and being in communication above the liquid level with the interior of said duct at the discharge side of said damper, the other of said chambers being open to the atmosphere, a tube communicating with said duct and extending outwardly into said other chamber to a point above the liquid level, an annular float mounted on the liquid in said other chamber and encircling said tube, a cap on said float telescoping with and substantially sealing said tube from the atmosphere, and a pivotal link connection between said cap and said damper extending through said tube, whereby said damper will be moved toward open position as said float rises in response to an increase in static pressure in said duct.

25 13. An automatic damper comprising, in combination with an air duct and means for supplying air under pressure to said duct, an adjustable damper in said duct, a liquid reservoir mounted over said duct and having two liquid 30 chambers in intercommunication below the liquid level, one of said chambers being closed to the atmosphere and being in communication above the liquid level with the interior of said duct, the other of said chambers being open to the atmosphere, a tube communicating with said duct and extending into said other chamber to a point above the liquid level, an annular float mounted in said other chamber and encircling said tube, and a connection between said damper 40 and said float extending through said tube, whereby said damper will be adjusted synchronously with the vertical movement of said float in response to variations in the static pressure in said duct.

45 CLARK SCHOLL.
